US00D897523S

(12) **United States Design Patent** (10) **Patent No.:** **US D897,523 S**
(45) **Date of Patent:** **** Sep. 29, 2020**

(54) **NASAL CANNULA BODY**

(71) Applicant: **Fisher & Paykel Healthcare Limited**,
Auckland (NZ)

(72) Inventors: **Sean Joel Babbage**, Auckland (NZ);
Peter Geoffrey Hawkins, Auckland (NZ); **Kevin Peter O'Donnell**,
Auckland (NZ); **Jason Allan Klenner**, Auckland (NZ); **Mark Thomas**
O'Connor, Auckland (NZ); **Milanjot Singh Assi**, Auckland (NZ)

(73) Assignee: **Fisher & Paykel Healthcare Limited**,
Auckland (NZ)

(**) Term: **15 Years**

(21) Appl. No.: **29/666,359**

(22) Filed: **Oct. 11, 2018**

Related U.S. Application Data

(60) Continuation of application No. 29/614,636, filed on Aug. 21, 2017, now Pat. No. Des. 834,703, which is a division of application No. 29/551,896, filed on Jan. 18, 2016, now Pat. No. Des. 796,027, which is a division of application No. 29/470,958, filed on Oct. 25, 2013, now Pat. No. Des. 747,792.

(57) **CLAIM**

The ornamental design for the nasal cannula body, as shown and described.

DESCRIPTION

FIG. 1 is a perspective view showing a nasal cannula body that embodies the design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is bottom view thereof.

Where utilized, the broken lines show portions of the nasal cannula body that form no part of the claimed design.

1 Claim, 7 Drawing Sheets
